CLAIM

The ornamental design for a control region for a cooking appliance, as shown and described.

DESCRIPTION

FIG. 1 is a front perspective view of a control region for a cooking appliance showing our new design;

FIG. 2 is a front view thereof;

FIG. 3 is a top view thereof;

FIG. 4 is a bottom view thereof;

FIG. 5 is a left side view thereof;

FIG. 6 is a right side view thereof; and,

FIG. 7 is a front perspective view of the control region for a cooking appliance of FIG. 1 shown on an exemplary cooking appliance.

The broken line showing the remainder of the control region and the cooking appliance is for environmental purposes only and forms no part of the claimed design.

1 Claim, 5 Drawing Sheets
